UNITED STATES PATENT OFFICE.

CHARLES FRANCIS JENKINS, OF WASHINGTON, DISTRICT OF COLUMBIA.

INTERNAL-COMBUSTION ENGINE.

1,098,805.

Specification of Letters Patent. Patented June 2, 1914.

Application filed July 8, 1911. Serial No. 636,764.

To all whom it may concern:

Be it known that I, CHARLES FRANCIS JENKINS, a citizen of the United States, residing at Washington, in the District of Columbia, have invented certain new and useful Improvements in Internal-Combustion Engines, of which the following is a specification, reference being had therein to the accompanying drawing.

10 Although two-cycle engines have marked advantages in simplicity and economy, their use is limited practically to cases where the load is fairly heavy or the speed uniformly somewhat high, for the reason that if it be desired to reduce the fuel supply as much as is desirable for light load or low speed explosions are missed, the unexploded charges are wasted, and other vexatious results follow.

20 The general object of this invention is to avoid these evils by providing a two-cycle engine of such character that the fuel supply may be reduced to any practically desirable extent without danger of missing explosions or introducing any harmful feature. With this object in view I provide a relatively small passage of a considerable length, for leading the explosive charge to the engine cylinder, and place an igniter 25 in this narrow passage at such distance from the working space in the cylinder that the entering gas while in the passage near the igniter is unaffected by any fluid that may be in, or may be thrown back 30 from, the cylinder itself. I further provide for throttling the entering gas at a point more distant than the igniter from the point where the fuel enters the cylinder. The igniter is thus at a point where the 35 entering gas, which may at all times be rich, has not been changed after entering the passage, and being highly combustible it is ignited with entire certainty. Thus 40 variation in power is secured by varying the quantity of the gas admitted without necessarily varying its quality. The passage being unobstructed between the igniter and the combustion space in the cylinder, it is obvious that the engine delivers substantially the full power of such charge, large 45 or small, as may be admitted, even if the entire space above the piston be filled partly or wholly with incombustible material.

In the accompanying drawings, Figure 55 1 shows a portion of an engine in side elevation with parts in section. Fig. 2 is a

similar view showing some of the same parts in different position. Fig. 3 is a detail plan view of certain throttling devices. Fig. 4 is an elevation, partly in vertical section, looking toward the right in Figs. 1 and 2. Fig. 5 is a section on the line 5-5, Fig. 2.

In these figures, A represents an engine cylinder, B its piston, C the crank case, 60 D the exhaust port, E a narrow passage, preferably in the cylinder wall, leading from a port F in the lower part of the cylinder to the space above the upper limit of the piston's path, and G an igniter 65 placed in the passage near the port F. The piston is provided with an internal passage H communicating with the crank case below and with a port H' in position to register with the port F when the piston is at its lowest point, and to permit gas to pass from the passage H into the passage E. The admission is governed, as to 70 periodicity, directly by the piston while the quantity admitted is controlled by a 75 slide valve I operated by the piston but so arranged that the degree of opening may be varied at will. This valve moves in a suitable way, to open and close the passage E near the port F or between that port 80 and the igniter, and is provided at its lower end with a projection J to be engaged by a projection or shoulder K upon the piston, as the latter ascends, so that the valve is carried upward and fully closed when the 85 piston reaches its highest point. Above the projection J, the valve is perforated and provided with an outwardly projecting ear L to which is pivoted a hand lever M the inner arm of which projects through 90 the opening in the valve into the path of a second projection or shoulder K' upon the piston, so that as the piston descends this projection or end of the lever M and the valve itself are moved downward. The 95 valve I works in a recess in the outer face of a block X fixed in a recess in the inner face of the cylinder and flush with the inner surface of the latter.

The outer arm of the lever is pivoted, at 100 an adjustable height, to a sleeve N upon a standard N' itself pivoted to swing in the plane of the lever, and thus as the valve moves up and down, the lever swings about the pivot upon the standard while the standard itself rocks slightly and the valve moves 105 in a fixed plane. The sleeve is locked to the

standard by a set screw O provided with a head adapting it for operating by the hand, and when this set screw is loosened the lever may be moved upward or downward and be 5 then again locked. The pivot at L is at some distance from the inner end of the lever, and hence raising or lowering the outer end of the lever, in the manner just described, moves its inner end downward 10 or upward. If it be moved upward to a certain point, the descending shoulder K' upon the piston will engage it sooner and will carry it and the valve farther down than when it is in a lower position of adjustment, and the valve will thus be fully 15 opened at the proper time for admitting fuel gas. If on the other hand the outer end of the lever be raised, throwing its inner end downward, the valve will be opened to an 20 extent depending upon the adjustment of the lever, and amount of fuel gas admitted during the period of admission will be correspondingly decreased; or in other words, the amount of fuel admitted will be 25 controlled by the operator.

It is evident that although the engine is of the simple two-cycle type, it may be operated at extremely low speed if desired, and yet act with all the certainty obtainable 30 at high speed or with any type of explosion engine.

It may be observed that the valve prevents possible back-firing, even if the piston be not capable of securing entire safety in this 35 respect since at the time of explosion it cuts off the passage F and is laterally seated by the pressure due to explosion. Usually the full capacity of the conduit or passage in which the igniter is located is far below the 40 volume of an ordinary charge of fuel, but in my case, it is indispensable that the igniter be located in a portion of a channel capable of containing but a fraction of an ordinary charge and in unobstructed communication 45 with the working space in the cylinder.

What I claim is:

1. In a two-cycle gas engine, the combination with a cylinder provided with a conduit leading from a port in the lower part of the 50 cylinder to the space above the upper limit of the piston's path, of a piston working in the cylinder and provided with a passage leading from its lower end to an opening in its lateral wall in position to register with 55 said port only at the proper time for admitting fuel to the cylinder, an igniter located in said conduit near said port, said conduit being unobstructed between the ig-

niter and said space, and automatic means for cutting off said conduit prior to each explosion, between said port and igniter. 60

2. In a two-cycle gas engine, the combination with a fuel containing crank case and an engine cylinder communicating therewith and provided with a passage leading from the lower portion of the cylinder into the space above the upper limit of the piston's path therein and having a total capacity equal to a small fraction of an ordinary charge, a piston working in the cylinder and provided with a conduit leading from the crank case to a lateral opening in position to register with the lower end of said passage only at the proper time for fuel admission, an igniter located in said 75 passage near the inlet end thereof, and a slide valve periodically actuated by the piston to cut off said passage between the igniter and said inlet end. 70

3. In a two-cycle gas engine, the combination with a fuel-containing crank case and an engine cylinder communicating therewith, of a conduit leading from the lower portion of the cylinder to the space above the upper limit of the piston's path and having that portion near its lower end narrow and adapted to be swept clear of other gas by entering fuel gas, a piston working in the cylinder and provided with a passage leading from its crank-case end to a lateral port 90 in position to register with the inlet end of said conduit only during the proper time for admitting fuel, and an igniter located in said narrow portion, said conduit being at all times unobstructed between the igniter 95 and said space.

4. The combination, in a two-cycle engine, of a cylinder provided with a conduit leading from its lower portion to the space above the upper limit of the piston's path, a piston working in the cylinder and provided with a passage leading from below to a lateral port in position to register with said conduit only at the proper time for fuel admission, means for supplying fuel to said 105 passage, a piston operated valve controlling admission of fuel to said conduit, means for at will varying the degree of the valve's opening, and an igniter located in said conduit. 110

In testimony whereof I affix my signature in presence of two witnesses.

CHARLES FRANCIS JENKINS.
